UNITED STATES PATENT OFFICE

2,358,381

OIL BURNER FOR STOVES AND THE LIKE

William T. Caley, Kalamazoo, Mich., assignor to
Kalamazoo Stove & Furnace Company, Kala-
mazoo, Mich., a corporation of Michigan

Application October 20, 1941, Serial No. 415,679

10 Claims. (Cl. 126—44)

This application is a continuation in part of my copending application Serial No. 366,133, filed November 18, 1940.

The main objects of this invention are:

First, to provide an improved sleeve-type oil or liquid fuel burner unit for stoves or heaters which is readily removable for servicing and replaceable without affecting the accuracy of positioning of the burner bases, a feature of very substantial importance in liquid fuel burners of the so-called sleeve type.

Second, to provide a liquid fuel burner unit having a rigid mounting for the bases and guide means or ways supporting the burner unit positioned remotely from the burners and the zone of intense heat resulting from their operation so as to prevent distortion or warping of such guide means or ways, the guide means or ways permitting the removal of the unit from the combustion chamber with which it is associated for cleaning and servicing and replacement without disturbing the setting of the burner bases.

Third, to provide a unitary sleeve-type oil burner construction including the burner bases or burners, a removable support therefor, and a supply reservoir on the support with fuel connections and valves for controlling the same, which construction is well adapted for use in many types of heaters.

Fourth, to provide a mounting unit for a sleeve type burner or burners which permits the burners to be moved only in a single plane parallel to the level of the burners.

Fifth, to provide a burner unit including a mounting therefor adapting the same for use in a range or other heater which compensates for and minimizes the effect of the natural expansion and movement of materials thereof in zones of varying temperatures.

Sixth, to provide a burner unit well adapted for use in various heater appliances, such as stoves or ranges, water heaters, space heaters and the like, to thereby reduce the cost and simplify the manufacture thereof on a commercial scale.

Objects relating to details and economies of the invention will appear from the description to follow. The invention is defined and pointed out in the claims.

A preferred embodiment of the invention is illustrated in the accompanying drawings, in which:

Fig. 1 is an end view of a stove or range embodying my invention partially broken away and in vertical section, the burner unit being shown

in full lines in operative position and partially withdrawn from the combustion chamber by dotted lines.

Fig. 2 is a fragmentary view in front elevation partially broken away and partially in broken section illustrating structural details of the burner unit and its supporting means and the relation of the parts in a combustion chamber and to other parts of the stove or range.

Fig. 3 is a fragmentary front elevation illustrating a portion of the stove adjacent the liquid fuel burner combustion chamber, the front closure member being open.

Fig. 4 is an enlarged fragmentary view illustrating details of the burner unit guides or slideways which coact with other parts to accurately support the burner unit while permitting its removal and replacement.

Fig. 5 is a side elevation illustrating the burner unit or assembly, the oil reservoir being indicated by dotted lines and the burner sleeves being in position on the burner bases.

Fig. 6 is a top plan view partially in horizontal section on line 6—6 of Fig. 5, the liquid fuel reservoir being removed.

Fig. 7 is a somewhat enlarged view in section on the broken line 7—7 of Fig. 5 showing certain details of the sump and burner connections.

Fig. 8 is a front elevation of the combustion chamber closure which constitutes a part of the assembly.

My present invention relates to a liquid fuel burner assembly which is particularly well adapted for fuel burners of the sleeve-type and I have illustrated it in that embodiment and in connection with a stove or range of the type shown in my copending application, Serial No. 366,133 above referred to of which this application is a continuation in part.

In the structure of the type of the said application, the liquid fuel burner unit coacts with the other features of the stove structure as described in said application, improving the efficiency of the structure including the oven and it will be appreciated from the description to follow that the present unit is adapted for use in other types of cooking stoves and heaters.

In the structure illustrated in the accompanying drawings, the reference numeral 1 in general designates a stove or range having a vertical partition 2 constituting the inner wall of a burner compartment or combustion chamber 3 at one end of the range, this partition constituting a side wall of the oven 4. The structure has insulated front, end and rear walls 5,

6 and 7 respectively, the front and rear walls being provided with aligned openings 8 and 9 respectively at the ends of the combustion chamber 3 for removable reception of the burner unit of my invention, which is generally designated by the reference numeral 10.

The combustion chamber 3 is provided with a bottom 11 which is designed to drain to the opening 12 which discharges to the drip pan 13 disposed beneath the bottom and removable through an opening 14 in the extension 15 of the front wall 5. At its top, the combustion chamber 3, in the embodiment illustrated, is in heat transfer relation to other parts of the stove as is described in the aforesaid application.

Within the combustion chamber and closely adjacent to the bottom 11 thereof, I mount a slideway comprising vertically disposed plate-like way members 16 having out-turned flange-like slide-way elements 17 at their upper edges. Within and secured to these way members 16 are auxiliary way members 18 having out-turned flange-like slideway elements 19 in spaced overhanging relation to the slideway elements 17. These slideway elements are longitudinally crowned or conformed to provide restricted slideway surfaces as indicated in Fig. 4, designated by the numerals 171 and 191, and these are adapted to springably receive the flange-like slide portions 21 of the slide members 20. The members 16 and 18 are fixedly secured together by spot-welding or otherwise as may be desired.

The slide members 20 are plate-like and of very substantial depth and they constitute a part of the burner supporting frame or structure, being rigidly connected to the cast iron frame members 22 as shown in Figs. 1, 2 and 6.

The burner bases 23 are mounted on the frame members 22 which are of general Y-shape, being provided with out-turned ears 25 bolted to the slide members 20 as shown in Fig. 6. The burner bases are adapted to receive a plurality of concentric burner sleeves 24.

The frame members 22 are drilled and tapped to receive the adjusting screws 26 which support the burner bases 23 and permit the supporting screws being adjustable to support the burner bases in a perfectly horizontal position when they are initially installed.

The fuel feed pipe 27 which supplies the individual liquid fuel to the burners is disposed at the juncture of the legs of the frame members 22 as illustrated. These feed pipes have supply fittings 28 connected thereto immediately below the frame members 22 as shown in Figs. 1 and 2.

At their ends, the members 20 are provided with inturned vertical flanges 29 to which are secured the front and rear closure members 30 and 31. These closure members are insulated as shown in Fig. 1 and fit the openings 8 and 9 at the front and rear of the combustion chamber, so that when the burner unit is in place, the combustion chamber has insulated walls on three sides thereof, the partition 2 being designedly without insulation in order that heat from the combustion chamber may be transmitted to the oven 4. These closure members in effect constitute a part of the burner supporting frame—that is, they constitute connecting members for the plate-like side members 20.

On the rear side of the rear closure member 31 I mount a bracket 32 to which is securely bolted a cast table member 33 having ears 34 adapted to receive the threaded supporting screws 35 of the fuel pan or sump 36. This fuel pan or

sump is adapted to receive the inverted reservoir 37.

The sump is dimensioned so as to pass through the front and rear combustion chamber openings 8 and 9 for assembly and removal. The sump 36 discharges by gravity through a strainer 38 to the oil pipe 39 in communication with the oil distributor pipe 40. The feed pipes 27 of the respective burners are communicated through conduits 41 with this distributor, and the flow of oil from the distributor through these feed pipes is controlled by individual valves disposed in fittings 42. In order to actuate these valves individually, I provide mechanical connections 43 extending from the valves longitudinally of and through the burner unit, including the front and rear closures 30, 31. The said connections include flexible guide portions 44 immediately adjacent the front of the front closure member 30, see Figs. 1 and 8, and control rods 45 slidable therein and guided in brackets 46 on the front of said closure. These last named rods are releasably connected with control elements or knobs 47 on the front of the range, whereby the burner unit is readily capable of being disassociated from the valve control knobs when it is desired to remove the unit for cleaning and/or servicing.

As stated, the burners are of the well known sleeve type and the sleeves thereof are removable from the respective burner bases 23 when the unit is taken out of the oil burner compartment. This removal is effected through an appropriate removably covered opening in the stove top above the compartment 3. The aforesaid burner unit is a very rigid, distortion-resistant one by reason of the rigidly connected and braced side plates 20 employed for guiding and supporting the burners. This rigidity is enhanced by the front and rear connections of said plates with closures 30, 31 and the resistance to distortion or wracking is further augmented by the fact that the side plates 20 are, as pointed out above, relatively high, thereby spacing the slides 21 and the coacting fixed guide ways a substantial distance below the comparatively hot zone adjacent the burner bases 23. Such a deep construction results in the guide elements being subjected to less intense heat and less radical changes in temperature. As pointed out above the special guide way structure illustrated in Fig. 4 insures a uniformly positive and unchanging frictional grip on the sides 21 of the side members 20 so that the relative positioning of the latter remains unchanged at this point regardless of the number of times the unit is removed and replaced. A door 49 is pivoted on the front of the stove casing to conceal the opening to compartment 3 and the burner operatively positioned therein.

The burner bases, following original setting by adjustment of their supporting screws 26, thereafter remain absolutely uniform in their elevation and level. This is an important factor in the operation of the sleeve type oil burner. Sleeve-type burners are decidedly preferable to other known type burners, for example, pot burners, by reason of the greater heating efficiency and cleanliness thereof. Notwithstanding the fact that sleeve burners predominate in actual use, they have certain objections which have prevented still more extensive adaptation thereof. In the first place, as stated above, they must be exceedingly accurately installed to bring the burner bases on a level; otherwise the efficiency and heat of combustion thereof which are their primary recommendation are lost. A discrep-

ancy of as little as .005 inch between the level of the burner and reservoir bases is sufficient to change the characteristic blue flame of these units to a wasteful, smoky yellow flame. Obviously only the greatest precautions will suffice to produce such an accurate alignment of the parts, once the burners have been removed for servicing, cleaning and the like. Secondly, they must be very frequently serviced, for the oil entering the same through the central aperture in the burner base is subjected to an oil cracking operation which results in the depositing of carbon around and adjacent the opening. This in turn will clog the opening unless it is frequently removed. Obviously, the removal and replacement of these units to the above mentioned extremely accurate level is a feat which is beyond the scope of the ordinary range owner, hence the expense of skilled servicing is usually entailed. So far as I am aware, no sleeve burner range unit has heretofore been devised which will allow ready dismounting so that the carbon removal can be thoroughly effected and re-installation in its necessary, accurate and exact operation position effected. Moreover, so far as I am aware, no one has ever devised a removable mounting for a sleeve type oil burner unit which is proof against distortion under the expansion and contraction to which it is subjected so as to enable removal and replacement at any time by unskilled persons and likewise prevent disturbing the proper level arrangement of the burners by thermal changes.

Though particularly designed for, and in the present application illustrated as, a unit for a cooking stove or range it will be evident from the foregoing description that it is equally well applied in other types of heaters, for example, water heaters, space heaters and the like, hence I do not wish to be unduly restricted in this respect.

An embodiment of the invention which incorporates the principles of the invention in a highly desirable manner has been illustrated and described, though I am aware that other embodiments within the intent of the invention will suggest themselves to those skilled in the art. It should be understood that the foregoing terminology is used only descriptively rather than in a limiting sense, and with full intention to include equivalents of the features shown and described, within the scope of the following claims.

Having thus described my invention, what I claim as new and desire to secure by Letters Patent, is:

1. In a structure of the class described, the combination of a combustion chamber having opposed front and rear openings, a removable burner unit comprising liquid fuel burners of the removable sleeve type, a supporting structure for said burners including spaced vertically disposed plate-like side members having inturned flange-like slideway-engaging slides at their lower edges, vertically disposed plate-like members mounted in said combustion chamber and having out-turned flange-like slideway elements at their upper edges, coacting auxiliary members mounted on the inner side of said last named plate-like members and having out-turned flange-like slideway elements at their upper edges disposed in spaced overhanging relation to said first named slideway elements, said slideway elements being inwardly and centrally crowned and coacting to provide slideways springably receiving said slides, and front and rear closure mem-

bers on said supporting structure coacting with said front and rear openings when the burner assembly is operatively positioned in the combustion chamber, said side members being of such vertical width that the slideways are substantially below the zone of intense heat adjacent the burners thereby preventing warping and distortion of the slideways.

2. In a structure of the class described, the combination of a combustion chamber having opposed front and rear openings, a removable burner unit comprising liquid fuel burners of the removable sleeve type, a supporting structure for said burners including spaced vertically disposed plate-like side members having inturned flange-like slideway-engaging slides at their lower edges, vertically disposed plate-like members mounted in said combustion chamber and having out-turned flange-like slideway elements at their upper edges, coacting auxiliary members mounted on the inner side of said last named plate-like members and having out-turned flange-like slideway elements at their upper edges disposed in spaced overhanging relation to said first named slideway elements, and front and rear closure members on said supporting structure coacting with said front and rear openings when the burner assembly is operatively positioned in the combustion chamber, said side members being of such vertical width that the slideways are substantially below the zone of intense heat adjacent the burners thereby preventing warping and distortion thereof.

3. In a structure of the class described, the combination of a combustion chamber, a removable burner unit comprising liquid fuel burners, a supporting structure for said burners provided with slideway engaging slides, coacting slideway elements disposed in said combination chamber and in superimposed relation, said slideway elements having inwardly and centrally disposed crowned portions coacting to provide slideways springably receiving said slides, liquid fuel supply means for said burners carried by said supporting structure externally of said chamber, means connecting said liquid fuel supply means to said burners and carried by said supporting structure, and means carried by said supporting structure for regulating the flow of fuel from said supply means to said burners, said slideways being substantially below the burners and remote from the zone of intense heat adjacent the burners, thereby preventing warping and distortion of the slideways.

4. In an oil heater of the type described, a burner unit comprising a distortion resistant support including vertically deep, plate-like side members having a burner base adjustably supported thereon and carrying burners, said side members being provided with slide elements in substantially spaced vertical relation to said base out of the zone of intense heat adjacent the latter and the burners thereon, a combustion chamber having front and rear openings, slideways mounted in said combustion chamber for positively frictionally engaging said slide elements to guide the support for longitudinal sliding movement in the direction of said openings, said unit comprising front and rear closures secured to the support and coacting with said respective openings when the unit is operatively positioned in the compartment, liquid fuel supply means including a sump and means connecting the same in fuel feeding relation to said burners, said sump and fuel supply means being mounted at

the rear of said rear closure member, and means carried by said support for regulating the flow of oil from said supply means to said burners, said support, burners, closures and supply means being simultaneously slidably lengthwise of said compartment for removal through one of said openings.

5. In a structure of the class described, the combination of a casing having a burner chamber therein provided with opposed openings in its front and rear walls, the casing being provided with a door covering the front opening space when closed, guide means disposed in said chamber, an oil burner unit comprising front and rear wall closure members for said front and rear wall openings and a connecting burner supporting frame to which said closure members are secured, said supporting frame being slidably engageable with said guide means, burners mounted on said frame and comprising a fixed burner base element and a top member removably engaged therewith, a fuel tank supporting bracket projecting rearwardly from the burner unit rear wall closure member, a removable fuel tank supported by said bracket, fuel supply connections from said fuel tank to said burners, a valve for said supply connections, and operating means for said valve carried by said burner unit, said burner unit being removable from said chamber as a unit, through the front wall opening.

6. In a structure of the type described, an insulated casing having a combustion chamber provided with front and rear openings, an oil burner in said chamber, a rigid, distortion resistant support for said burner in the combustion chamber, guide means in the combustion chamber on which said support is slidably mounted for longitudinal movement and maintaining the burner on a level in the chamber, said support having a front closure plate secured thereon removably coacting with said front opening and having a rear insulated closure secured thereon coacting with said rear opening, a supporting bracket on said rear closure extending externally thereof, fuel reservoir structure on said bracket, and feed connections from said reservoir structure to said burner, said support, burner and reservoir structure being removable from said casing as a unit through one of said openings for cleaning and the like.

7. In a structure of the type described, a casing having a combustion chamber provided with openings in the front and rear walls thereof, a liquid fuel burner in said chamber, a rigid, distortion-resistant support for said burner in the combustion chamber, guide means in the combustion chamber on which said support is slidably mounted for longitudinal movement and maintaining the burner on a level in the chamber, said support having a closure secured thereon coacting with the opening in the rearwall, a supporting bracket on said closure extending rearwardly and externally of said closure and combustion chamber, a liquid fuel reservoir supporting structure on said bracket, and feed connections for connecting a reservoir on said reservoir supporting structure to said burner, said support, burner and reservoir supporting structure being removable from said combustion

chamber as a unit through the front opening for cleaning and the like.

8. In combination with a range of the type described having an oven and a combustion chamber at one side thereof provided with front and rear openings, a rigid distortion resistant support having a plurality of sleeve type oil burner members thereon, said support being disposed horizontally in said chamber and having vertically extending supporting guide means, said chamber having guide way means slidably receiving said guide means to enable removal of the support from the chamber and replacement therein, said guide means extending for a substantial distance vertically whereby to space the support substantially above said guide way means and thereby minimize distortion or wracking of the guide means adjacent the guide way means under the influence of heat in the chamber adjacent the support, said support being provided with a pair of closures coacting with said front and rear openings, through one of which the support is removable, and a fuel supply reservoir member secured to said support externally of one of said closures, said burners, closure and reservoir member being removable from said casting with said support as a unit for cleaning and the like.

9. In combination with a range of the type described having a combustion chamber provided with opposed openings in the front and rear walls thereof, a rigid, distortion resistant support having a sleeve type oil burner member thereon, said support being disposed horizontally in said chamber and having supporting guide means, said chamber having a guide way means slidably receiving said supporting guide means to enable removal of the support from the chamber and replacement therein, said support having secured thereon a closure coacting with the rear opening in the combustion chamber, and fuel supply means secured to said support externally and rearwardly of said closure and said combustion chamber, said burner being removable from said combustion chamber through the front opening together with said support, closure and supply means as a unit for cleaning and the like without disturbing the relation of the burner on the support.

10. In a structure of the type described, a combustion chamber provided with opposed openings in the front and rear walls thereof, a liquid fuel burner in said chamber, a support in said chamber for said burner, guide means in said chamber and on which said support is slidably mounted in alignment with said openings, said support having a closure thereon coacting with the opening in the rear wall, a liquid fuel reservoir supporting structure disposed exteriorly of said chamber and rearwardly of said closure and movable with said support, feed connections for connecting a reservoir on the reservoir supporting structure to the burner, said support, burner and reservoir supporting structure being removable as a unit from the chamber through the opening in the front wall, and a closure for the last mentioned opening.

WILLIAM T. CALEY.
